UNITED STATES PATENT OFFICE

2,399,077

POWER LIMITING CARBURETOR

Stanley M. Udale, Detroit, Mich., assignor to
George M. Holley and Earl Holley

Application May 10, 1940, Serial No. 334,328

5 Claims. (Cl. 261—50)

The object of this invention is to open the fuel nozzle manually and to open the throttle automatically and by this means, assuming a constant pressure for the fuel, a definite quantity of fuel will be admitted when the fuel needle is wide open. This means that only a definite amount of power can be developed, assuming that the air flow is controlled by the fuel flow. There will, therefore, be no need for a separate power control, as power control will be inherent in such a device. At any given fuel flow the object is to adjust the air flow to correspond to the fuel flow. Obviously, after the air throttle has been automatically opened as wide as possible, then as the plane continues to ascend it will be necessary to automatically close the fuel to maintain the mixture constant when the throttle is wide open at high altitudes. Hence the automatic mixture control must first open the throttle and dilute the mixture with air, and then close the fuel valve with the throttle wide open, so that the mixture ratio may be maintained at the cruising lean ratio at high altitudes.

Figure 1 shows diagrammatically the applicant's invention based in part on the disclosure in patent to Lundgaard 1,333,986.

Figure 2 shows a sectional plan view taken on plane 2—2 of Figure 1 looking down.

In the drawing, 10 is the air entrance, 11 is a venturi in the air entrance, 12 are the orifices communicating with the annular chamber 13 which surrounds the venturi, 14 is the chamber containing the aneroid barometric elements 15, which control the lever 16 pivoted at a fulcrum 17 eccentrically mounted in a bearing 18 controlled by a lever 19. This eccentric support which is provided for the pivots 17 permits an adjustment to be made in flight. The barometric elements 15 contain an inherent spring in the material of which they are made, or a spring is added, or they contain air. The lever 16 is connected by the link 15 with the link 16 which has a fulcrum at 20 and carries a pin 25.

The annular chamber 13 communicates with the chamber 21 which is closed on its right hand side by the diaphragm 22. This diaphragm is connected by the link 23 with the lever 24 pivoted on the pin 25 carried by the lever 16. The lower end of the lever 24 is pivotally connected with the link 26 connected to a diaphragm 27 which forms the right hand wall of a chamber 28, which chamber communicates through the pipe 29 with the throat of the fuel venturi 30 located downstream from a fuel entrance 34 connected with a source of fuel under constant pressure.

A similar fuel chamber 31 is formed with a

similar diaphragm 77 which is connected by a similar link 33 with the lever 24 at the same pivot to which link 26 is attached. The pressure in the chamber 31 corresponds to the pressure in the fuel entrance 34. The diaphragms 77 and 27 of chambers 31 and 28 are of equal size.

The upper end of the lever 24 is connected by means of the link 35 with the valve 36 which controls the servo mechanism 37. This servo mechanism comprises a piston 78 and operates a roller 38 which engages with the cam surface 39 of the bell crank lever 51 mounted on the throttle shaft 40 which shaft moves the throttle 41, shown in broken lines. The source of working fluid for the servo motor is not shown as this servo motor is not applicant's invention and servo motors are now in universal use on airplanes and their function and their details of construction are well known.

20 An idle stop 73 prevents the complete closure of the throttle 41.

A fuel orifice 42 is controlled by a movable needle valve 43 which engages with the cam surface 44 of the bell crank lever 46 and is held in contact therewith by means of the compression spring 45. Another bell crank lever 47 is mounted on a pin 48 on a bracket 49. A rod 50 is connected with any suitable manual control for opening and closing the fuel valve 43. When the rod 50 is

30 pushed up to permit the fuel valve to open, it pushes the rod 52 against the bell crank lever 51 and compresses the spring 53 and also opens the throttle 41 slightly, but in such a way that the mixture remains on the rich side but not so rich as to stall the engine. At the same time the lever 47 carries the adjustable stop 54 to the right, permitting the cam surface 44 also to move to the right under the influence of the compression spring 45. The rod 52 moves relatively less than 40 the needle 43 so that the mixture is rich. As the fuel flows through the venturi 30 and the air flows through the venturi 11, pressure differentials are set up in the throats of the two venturis. The depression in the fuel venturi 30 is established in 45 the chamber 28 and the depression in the air venturi 11 is established in the chamber 21.

Assuming that the mixture is rich, then the lever 24 is moved clockwise slightly by the lack of balance due to the relatively excessive flow of 50 fuel through the venturi 30 as compared with the flow of air through the venturi 11. The effect of the depression due to velocity in these two venturis acting on the three diaphragms 22, 27 and 77 disturbs the equilibrium of the lever 24 and 55 moves the valve 36 to the right, causing the servo

piston 18 also to move to the right, carrying the roller 38 against the cam surface 39 of the lever, so as to open the throttle 41 to lean out the mixture until the desired cruising lean mixture is obtained.

Obviously as the plane ascends into the air, an altitude is reached at which the throttle 41 becomes wide open and the fuel flowing through the venturi 30 continues to be at its definite maximum flow, so that thereafter the mixture would become progressively richer. To prevent this, the roller 38 then engages with the cam surface 55 of the lever 56 pivoted at 57 on the air entrance. When the lever 56 is thus rotated anti-clockwise it engages with the roller on the end of the rod 58, by which means the rod 58 is forced down and engages with the bell crank lever 46 and the cam surface 44 presses against the head of the needle 63 and thus reduces the size of the orifice 42 compressing the spring 45 and restricting the fuel flow until equilibrium between the two venturis is once more established.

The air entrance 59 leads to a passage 60 which discharges through an opening 61 together with the fuel issuing from the orifice 42. The fuel thus discharges under substantially atmospheric pressure at all throttle positions, as the air entrance 59 is connected to the air entrance 10 of the carburetor by a pipe 74. The fuel issuing through 42 thus discharges under atmospheric pressure and thus the maximum flow is constant regardless of the position of the throttle 41. For this reason the maximum amount of fuel flowing through the venturi 30 is a constant amount determined by a stop 62 which limits the clockwise movement of the bell crank lever 46 and therefore determines the maximum opening of the orifice 42. This stop 62 therefore acts as an adjustable power control.

To adjust for idle a stop 73 limits the closing of the throttle 41. The stop 73 in conjunction with the adjustable stop 54 on the lever 47 determines the minimum opening of the orifice 42 and the minimum opening of the throttle 41.

It is desirable to increase the richness of the mixture at wide open throttle at maximum speed, especially when running in conjunction with air cooled engines. To get this extra fuel the invention of M. E. Chandler, Patent 2,125,886, is incorporated with this invention as follows:

The passage 64 leads from the chamber 31 to the chamber 65. A passage 66 leads from the chamber 28 to a chamber 67. A diaphragm 68 is located between the two chambers 65 and 67, and is connected to a needle 69 and is supported by a spring 70 located in the cover 71 which encloses the chamber 67. The fuel discharging past the needle 69 is delivered to the air flowing up through the passage 60. Hence this fuel discharges into a chamber connected with the air entrance 59, connected with the air entrance 10. The fuel therefore discharges against the atmospheric pressure. Assuming that the pressure in the fuel entrance 34 is constant, and this will be true within a range of plus or minus two per cent, any pressure differential between the venturi 30 and the fuel entrance 34 will give a definite increment to the mixture ratio determined by the taper of the needle 69 and the stiffness of the spring 70.

A spring 53 is available for maintaining the cam surface 39 in contact with the roller 38 and a similar spring supports the lever 56 which carries the cam surface 55 with which the roller 38 ultimately engages.

The movement of the pin 25 in response to variations in altitude is necessary to correct for the change in air density. So long as air density remains at sea level density, the flow through the venturi 13 and the venturi 30 increases and decreases at the same rate for variations in fuel flow and air flow, thereby maintaining a constant mixture ratio. If we assume the air density becomes one-half that of the atmosphere at sea level, then the effect of any given velocity is one-half, that is to say, the suction in the chamber 21 is one-half what it would be at sea level. The suction in the chamber 28 would also be one-half the suction at sea level. The density of the fuel will not change and therefore the velocity through the venturi 30 would be $\frac{1}{\sqrt{2}}$ of the velocity at sea level for equilibrium. Therefore, the weight of fuel would be $\frac{1}{\sqrt{2}}$ and the weight of air would only be 50%, so that the mixture ratio would be 40% richer, and to correct this the pin 25 moves up at altitude so that the leverage of the fuel flow increases and the leverage due to air flow decreases, and therefore a greater volume of low density air flow is necessary to balance a given fuel flow when the air is at low density.

What I claim is:

1. A carburetor having an air entrance, a venturi therein, a throttle valve, an air outlet, a fuel nozzle having a discharge orifice discharging therein, a valve controlling said orifice, a fuel passage leading to said orifice, a venturi therein, a servomotor, a valve control therefor, means responsive to the depression in the air entrance 30, venturi, and means responsive to the depression in the fuel venturi, said means being adapted to act in opposition to each other for the control of said servomotor valve, operating means connected to the servomotor adapted to open the throttle and means whereby after the air throttle is wide open, the continued motion of the servomotor is adapted to close the fuel valve, manual means for permitting the fuel valve to open, a one-way connection from the manual control means to the throttle valve whereby when the fuel valve is permitted to open the throttle valve is opened a limited amount to provide the necessary rich mixture for acceleration.

2. In a carburetor, a source of fuel supply under pressure, a fuel passage leading therefrom, a restriction therein creating a pressure difference proportional to the square of the velocity of the fuel, a fuel outlet, fuel throttling means therein, an air passage, a restriction therein creating a pressure difference proportional to the square of the velocity of the air, a throttle in the air passage, mechanism responsive to the simultaneous effect of the relative pressure difference created by the fuel flow as compared with the similar pressure difference created by the air flow, the effect of excessive air flow tending to automatically close the throttle and the effect of excessive fuel flow being adapted to automatically open the throttle in the air passage after the fuel restricting means is opened, whereby the air flow is increased and the two devices responsive to the said pressure difference are balanced, and additional means responsive to the fuel flow for moving the fuel restricting means to a more restricted position automatically after the air throttling means has been opened wide.

3. In a carburetor, a source of fuel supply under pressure, a fuel passage leading therefrom, a restriction therein creating a pressure difference proportional to the square of the velocity of the

fuel, a fuel outlet, fuel throttling means therein, an air passage, a restriction therein creating a pressure difference proportional to the square of the velocity of the air, a throttle in the air passage, mechanism responsive to the simultaneous effect of the relative pressure difference created by the fuel flow as compared with the similar pressure difference created by the air flow, the effect of excessive air flow tending to automatically close the throttle and the effect of excessive fuel flow being adapted to automatically open the throttle in the air passage after the fuel restricting means is opened, whereby the air flow is increased and the two devices responsive to the said pressure differences are balanced, and means responsive to the air density for changing the mechanical advantage of the air flow responsive elements over the fuel flow responsive elements whereby the pressure difference due to the fuel flow is more effective at high altitude so as to oppose a greater pressure difference due to air flow for a given fuel flow and thereby maintain the mixture ratio constant at altitude.

4. A carburetor having an air entrance, a venturi therein, a throttle valve, a mixture outlet, a fuel nozzle having a discharge orifice therein, a valve controlling said fuel orifice, a fuel passage leading to said orifice, a venturi therein, a servomotor, a valve control therefor, means responsive to the difference between the respective depre-

sions in the fuel venturi and in the air venturi for controlling the valve of said servomotor, said servomotor being adapted to first open the throttle valve, said servomotor being adapted after the throttle valve is fully open to move the fuel valve to a fuel flow restricting position, manual control means for limiting the opening movement of the fuel valve, and a stop for limiting the opening movement of the fuel valve.

5. In a fuel-air mixture ratio control device, a fuel entrance, a restricted fuel passage therein, a fuel outlet passage leading therefrom, a fuel throttle valve therein, a fuel throttle lever therefor, an air entrance, an air venturi therein, an air outlet, air throttling means located in said outlet, means responsive to the pressure difference created by said restriction in said fuel passage, additional means responsive to a similar pressure difference created by said air venturi, a mechanical connection between the two pressure responsive means adapted to bring into opposition with each other the two resultant forces produced by the two pairs of pressures, means responsive to the unbalance between said two opposing forces adapted to open said air throttle in response to an increase in fuel flow, means responsive to the opening of said air throttle to its wide-open position to close said fuel throttle valve independently of said fuel throttle lever.
